SAND BOX COVER

Daniel Allcott Kelly, Milwaukee, Wis.

Application December 31, 1952, Serial No. 329,054

4 Claims. (Cl. 291—38)

This invention appertains to railroad equipment, and more particularly to a novel cover for sand boxes of the type used on diesel engine units.

In order to insure a water-tight and moisture proof closure for sand boxes, it has been proposed to use inner and outer doors for the boxes. The opening and closing of such doors and the relation of one door to the other and to their frames, has met with certain objections between railroads and their workmen.

One of the primary objects of my invention is to provide a sand box cover embodying inner and outer doors with a novel connection between the same, whereby upon the opening and closing of the outer door, the inner door will be automatically actuated therewith.

Another salient object of the invention is to provide a novel arrangement of springs for the doors, whereby the doors will automatically snap open and closed upon actuation of the outer door beyond a certain position in the opening and closing movement, and in which the springs will function to continuously hold the doors sealed when the doors are in their closed position, the springs functioning in such a manner that upon failure of either spring, the remaining spring will act to hold both doors closed.

A further object of the invention is to provide a novel connection between the doors, and a novel spring arrangement including a heavy torsion spring and a lighter tensioned coil spring, so that each door has a certain movement independent of the other, whereby should one door be held partially open (through the meeting of an obstruction), the other door will be firmly and tightly moved and held in its closed position.

A still further object of my invention is the provision of a novel mounting for the screen in the chute carried by the inner door, whereby the screen can swing relative to the chute in an upward direction and away from the sand in the box in case the box is over-filled with sand, so that the screen will not impede the proper closing of the inner door.

With these and other objects in view, the invention consists in the novel construction, arrangement and formation of parts as will be hereinafter more specifically described and claimed, and illustrated in the accompanying drawings, in which drawings,

Figure 1 is a front elevational view showing my improved cover mounted on the side of an engine unit, only a fragment of the unit being shown, parts of the view being shown broken away and in section to illustrate structural detail.

Figure 2 is a vertical sectional view through the cover and engine unit taken on the line 2—2 of Figure 1 looking in the direction of the arrows, the view showing both the inner and outer doors in their closed, sealed positions in full lines and showing the outer door in its partially opened position in dotted lines, and its movement relative to the inner door prior to the actuation and opening of the inner door.

Figure 3 is a view taken at right angles to Figure 2 and through the cover, on the line 3—3 of Figure 2, looking

2

in the direction of the arrows, the view showing the inner door in its closed position and the relation of the torsion spring relative to the tension spring.

Figure 4 is a horizontal sectional view through the cover taken on the line 4—4 of Figure 2, looking in the direction of the arrows, the view showing the inner and outer doors in their closed position.

Figure 5 is a view similar to Figure 2, but showing both the inner and outer doors in their fully opened positions to permit the loading of the box with sand.

Figure 6 is a view similar to Figure 2, but showing the inner door held open by an obstruction and the outer door in its perfectly sealed, closed position.

Referring to the drawings in detail, wherein similar reference characters designate corresponding parts throughout the several views, the letter C generally indicates the novel cover for a sand box B.

The sand box B is of a type commonly used in the track sanding equipment employed on diesel engine units, a fragment of such unit being shown in Figures 1, 2, 4, 5 and 6, and indicated by the reference character U. As set forth above, only a fragment of the engine unit U has been shown, and in fact, merely the outer shell wall 10 has been illustrated, and this shell wall is provided with an opening 11 which receives the outer frame 12 for the cover. The sand box B is disposed interiorly of the unit U and includes an upstanding throat portion 13 leading from the box proper and terminating in a hood 14 opening toward the frame 12.

Now referring to the frame 12, the same is preferably in the nature of a casting, shaped to fit the opening 11, and includes a body portion 15 of a U-shape in cross-section and this body supports an outwardly extending attaching flange 16. The body portion 15 fits directly and snugly within the opening 11, and the flange 16 engages the outer surface of the wall or skin 10 of the unit. The flange is welded or bolted, as at 17, to the unit. Fitted within the body portion 15 is a gasket 18 which projects outwardly from the body and this gasket performs the function of a seal for the closure and a bumper, as will more fully appear. The gasket 18 can be made from any desirable material, such as rubber.

The cover C includes an outer door 19 and an inner door 20, and the doors are provided respectively for closing the frame 12 and the opening in the hood 14 of the sand box B. In the present instance, I have shown the doors 19 and 20 assembled in a complete unit structure and consequently, I secure to the body 15 of the frame 12, by bolts 21, an inwardly projecting shell or housing 22. The housing or shell 22 corresponds somewhat to the shape of the frame 12, and includes top and bottom walls 23 and 24, and side walls 25. The forward edges of the top and bottom walls 23 and 24 and the side walls 25 have formed thereon laterally projecting flanges 26, through which the bolts 21 extend and if desired, sealing gasket 27 can be interposed between the flanges 26 and the body portion 15 of the frame 12. The shell or housing 22 extends into the hood 14 of the sand box B and the rear end of the shell or housing is provided with an opening 28, which communicates with the sand box and the inner door 20 closes this opening 28. The opening can be surrounded by a sealing and bumper gasket 29. In certain installations on certain characters of units U, the frame for the inner door 20 is mounted independently of the front frame 12 and in which instance a flexible hood is utilized for uniting the frames for the inner and outer doors 19 and 20.

The hinge mounting for the doors 19 and 20 can be as follows. The lower end of the frame 12 has formed thereon outwardly projecting hinge lugs 30 and the lower edge of the door 19 has formed thereon an elongated

hinge barrel 31. A hinge pin 32 passes through the hinge lugs 30 and the barrel 31. Preferably, the hinge barrel 31 is elongated in cross-section whereby a loose play will exist between the door 19 and its frame 12, whereby the door under spring pressure will effectively seat itself against the gasket 18. At this point, it is to be noted that the marginal edges of the door 19 are inturned, as at 33, for movement toward the body 15 of the frame 12 around the gasket 18.

The inner door 20 is preferably formed from lighter material (such as sheet metal) than the outer door 20 and this door adjacent to its lower end has secured thereto hinge leaves 34. Mating edge leaves 34' are secured to the bottom wall 24 of the shell or housing 22, and a hinge pin 35 is inserted in the mating barrels of the hinge leaves 34 and 34'. From the construction so far, it can be seen that the inner and outer doors 19 and 20 are mounted for swinging movement independent of one another, for closing respectively the frame 12 and the opening 28. The inner and outer doors are provided with certain adjuncts, and as illustrated the outer door 19 has molded therein a hand grip 36 and on its inner face well above its hinge point inwardly directed, spaced bracket arms 37 and seats 38. The inner door has secured thereto, adjacent to its lower end outwardly projecting seats 39. Also secured to the outer face of the door 20, adjacent to its upper edge, are spaced pivot ears 40.

As brought out in the objects of the invention, the main features of the invention reside in a novel spring arrangement and a novel connection between the doors. The novel connection between the doors includes a plunger rod 41 terminating at its upper end in a head 42. The head 42 is disposed between the hinge lugs 40 and a pivot pin 43 extends through the lugs 40 and the head 42, whereby the plunger rod 41 is free to swing relative to the inner door. The plunger rod 41, adjacent to its lower end is provided with a longitudinally extending slot 44, which slidably receives a cross pin 45.

Upon the opening of the outer door 19, see Figures 2, 5 and 6, the cross pin 45 will move the length of the slot 44 before the inner door 20 is disturbed from its closed position, and hence, it now can be seen that the doors 19 and 20 have limited swinging movement relative to one another and independent of their connection. This is important, as will later appear. When the cross pin 45 reaches the end of the slot 44 there is a direct pull on the plunger rod 41 by the cross pin 46 and the inner door 20 will then move open upon continued opening movement of the door 19.

With both inner and outer doors closed, the compression spring 47 functions to hold both the inner and outer doors 19 and 20 in their closed, sealed position.

The doors 19 and 20 are also connected by a torsion spring 48 of a particular design. The torsion spring 48 includes a centrally disposed U-shaped connecting portion 49 terminating in laterally projecting coils 50 and these coils or convolutions 50 have formed on their outer terminals, depending arms 51. The lower ends of the arms are provided with hooks 52, which are anchored to the lugs 39 carried by the lower end of the inner door 20. The bight of the U-shaped connecting body portion 49 of the spring is anchored to and in the sockets 38, and hence the torsion spring on the opposite sides of its coils 50 are secured to the inner and outer doors 19 and 20. It will be noted that the point of connection of the torsion spring 48 with the outer door 19 is well above the hinge pin 32 of the outer door.

With the inner and outer doors closed (see Figure 2) the coils 50 of the torsion spring forcibly push the arms 51 of the torsion spring against the inner door 20 and the U-shaped connecting body portion 49 away from the outer door 19 to hold both doors in their closed positions. With both doors closed, the compression spring 47 and the torsion spring 48 both function to hold the doors closed. Due to the spring arrangement and the

sliding pin connection between the inner and outer doors, the inner and outer doors have limited movement independent of each other, and consequently, should either one of the doors meet with an obstruction during their closing movement, the remaining door can continue to its closed sealing position.

Initial opening movement of the outer door is resisted both by the compression spring 47 and the torsion spring 48, and as the pin 45 reaches the end of the slot 44 in the plunger rod 41 and the coils 50 of the torsion spring move over the pivot pin 32 of the outer door 19, a neutral position of the springs is reached. Upon continued opening movement of the door 19 a direct pull will be had on the inner door 20 and the convolutions or coils 50 of the torsion spring 48 will move over the pivot point of the door and the torsion spring then acts to forcibly snap open the door 19 to the position shown in Figure 5 and both doors are held open by the torsion spring.

The closing of the door 19 is resisted by the torsion spring until the neutral position is reached, and when the convolutions of the torsion spring are swung over and inwardly of the pivot point of the door 19 the torsion spring and the compression spring will both function to snap the doors to their closed, sealed position.

The inner door 20 has secured to its outer face spaced striker strips 53, and these strips hit the door frame 12 as shown in Figure 5, when the doors are open to limit the downward swinging movement of the doors.

The inner door has also secured to its inner face a chute 54, which guides the sand into the box B during the shoveling of the sand by the workmen through the door openings. This chute carries a screen 55 which prevents the entrance of solid objects, such as stones and pieces of iron, into the sand box with the sand, and in accordance with my invention, I connect the screen 55 by a hinge 56 with the lower rear edge of the chute. Consequently, if the box B is over-filled with sand, the screen 55 can move up (see Figure 2), away from the sand, allowing the complete closing of the inner door. The edge of the chute can cut through the pile of sand. If the sand is piled to an extremely high point in the throat of the box, and the chute prevents the closing of the inner door, see Figure 6, the outer door can continue to move to its closed position, as heretofore described and it is again reiterated that each door can close independently of the other.

Changes in details may be made without departing from the spirit or the scope of the invention, but what I claim as new is:

1. A cover for locomotive sand boxes comprising inner and outer spaced hinged doors, and a spring connection between said doors movable with the outer door upon the opening and closing of said outer door and said spring connection including convolutions and depending terminal members secured respectively to the inner faces of the inner and outer doors, the convolutions being movable over the hinged point of the outer door and toward said inner door during the closing movement of the outer door for snapping both of said doors to a closed position and said convolutions being movable over the hinge point of the outer door out from the inner door to snap both of said doors open upon downward opening movement of the outer door.

2. A cover for locomotive sand boxes comprising inner and outer spaced hinged doors, an operative connection between said doors including an inwardly extending bracket arm carried by the inner face of the outer door above its hinge point, a plunger rod pivotally secured to the inner face of the inner door above the hinge point of the inner door and said bracket arm, the plunger rod having a longitudinal slot therein adjacent to its lower end, a cross pin slidably in said slot carried by the bracket arm and a compression spring coiled about said plunger rod

and confined between the cross pin and the upper end of the plunger rod.

3. A cover for locomotive sand boxes comprising inner and outer spaced doors mounted at their lower ends for swinging movement, and an operative connection between the inner and outer doors including a plunger rod pivotally secured at its upper end to the inner door and projecting downwardly toward the outer door and terminating at a point above the fulcrum point of the outer door, a cross pin carried by the outer door disposed normally above the fulcrum point of the outer door, said plunger rod having a longitudinally extending slot slidably receiving the cross pin, a compression spring coiled about the plunger rod and confined between the pin and the upper end of the plunger rod, and a torsion spring including side convolutions and a connecting U-shaped portion anchored to the outer door at a point materially above the fulcrum point of the outer door and depending terminal legs anchored to the inner face of the inner door adjacent to the pivot point of said inner door, said convolutions being

20

movable over and beyond the pivot point of the outer door for snapping the inner and outer doors open and closed depending upon the direction of movement of the outer door.

5. A cover for locomotive sand boxes, an inner door mounted for swinging movement, an open ended chute secured to the inner face of said inner door and movable into the box when said door is closed, a screen for said chute hinged to the inner end of said chute and movable into the chute upon the engagement of the screen plate with an obstruction.
